UNITED STATES PATENT OFFICE.

THOMAS P. CALLOCOTT, OF PRESCOTT, ARKANSAS.

CHURN.

1,016,474.

Specification of Letters Patent.

Patented Feb. 6, 1912.

Application filed June 5, 1911. Serial No. 631,251.

To all whom it may concern:

Be it known that I, THOMAS P. CALLOCOTT, a citizen of the United States, residing at Prescott, in the county of Nevada and State 5 of Arkansas, have invented certain new and useful Improvements in Churns, of which the following is a specification, reference being had to the accompanying drawings.

This invention relates to improvements in 10 churns of that type employing a vertical reciprocating dasher and has for its primary object the provision of simple and efficient means whereby the dasher may be easily and quickly connected or disconnected to and 15 from the reciprocating pitman.

A further object of the invention is to provide a vertical frame having a crank shaft mounted therein, a pitman connected to the crank shaft, a sectional block connected to 20 said pitman, and a novel guide-way for said block whereby the sections may be separated to remove the shank of the dasher whereby the same is disconnected from the pitman.

Another object of the invention is to provide 25 a very simple and durable construction of the above character, such construction enabling the dasher to be removed and cleaned whereby the churn is maintained in a sanitary condition.

With the above and other objects in view, 30 the invention consists of the novel features of construction, combination and arrangement of parts hereinafter fully described and claimed, and illustrated in the accompanying drawings, in which—

Figure 1 is a front elevation of a churn embodying my improvements; Fig. 2 is a section taken on the line 2—2 of Fig. 1; Fig. 3 is a section taken on the line 3—3 of 40 Fig. 2; and Fig. 4 is a detail perspective view of one of the sliding block sections and a fragment of the dasher shank.

Referring in detail to the drawing 5 designates a vertical frame which consists of 45 the lower spaced uprights or legs 6 and the body 7. This body is provided with a longitudinal slot 8. Upon the upper end of the frame a crank shaft 9 is mounted in suitable bearings 10, the crank 9' of the shaft being 50 disposed in the slot 8 of the frame. To the crank 9' one end of a pitman 11 is connected, said pitman being adapted to work in the slot 8. One end of the crank 9 is provided with a handle 12 and to the other end there- 55 of a belt wheel 13 is secured. This wheel is traversed by the driving belt 14 which

passes around a belt wheel 15 mounted in a suitable bearing 16 secured to one of the spaced legs 6 of the frame. The shaft 17 of this lower belt wheel also has a hand crank 60 formed on each of its ends whereby said belt may be moved to rotate the upper crank shaft 9 and impart reciprocatory movement to the pitman 11.

The body 7 of the frame structure below 65 the slot 8 is provided with a vertical groove or channel 18 in line with said slot and in this groove the sliding block sections 19 and 19' are arranged. These block sections at one of their ends are bifurcated as indicated at 70 20 and they are each provided with the bearing recesses 21 to receive the ends of a wrist pin 22 which is fixed in the lower end of the pitman 11. The block section 19 is rabbed at its opposite longitudinal edges as 75 indicated at 23 to receive the opposed edges of the movable retaining bar sections 25 which are hingedly connected to the stationary sections 24 by means of suitable hinges 26. The lower ends of the movable sections 80 25 are provided with suitable thumb screws 27 which are adapted to be threaded into the frame 5 to rigidly secure said movable sections upon the frame. When so disposed it will be obvious that all tendency of the block 85 sections 19 and 19' to move out of the channel or groove 18 in the frame is overcome. The lower ends of the sliding block sections 19 and 19' are also provided with the substantially triangular-shaped recesses 28 90 95 which receive the flared rectangular end 30 of the dasher shank 29. By thus connecting the dasher to the sliding blocks, it will be seen that in the operation of the device, a reciprocatory movement will be imparted to the dasher, and all liability of its disconnection from the sliding block sections is obviated while at the same time, when the churning operation is completed the dasher may be readily removed.

In the practical use of my invention, the churn vat or tub is arranged between the ends of the uprights or legs 6 of the frame which are preferably secured upon a suitable base, and the movable retaining bar 105 sections 25 are raised. The outermost block section 19 is then lifted from the face of the other block section 19' and the flared end 30 of the dasher shank is seated in the recess 28 of the last named block section. The 110 outer section 19 is then disposed upon the same, the bearing recesses 21 receiving the

wrist pin 22 of the pitman. The lower movable bar sections 25 are then returned to their normal positions and rigidly fastened upon the frame body by means of the screws 27. The device is now in condition to be operated by simply turning either of the cranks 9 or 17. When the churning operation has been completed, the dasher is removed in a similar manner, so that it may be readily cleaned and the churn vat removed from its position between the uprights 6.

From the foregoing it is thought that the construction and operation of my improved churn will be readily understood.

The device is extremely simple, efficient and by means of the construction described the churn may be at all times kept in a sanitary condition. The connection of the dasher shank to the sliding blocks may be easily and quickly made. The device is also very durable and may be manufactured at a comparatively small cost.

While I have shown and described the preferred construction and arrangement of the various parts, it will be understood that the device is susceptible of considerable modification without departing from the essential feature or sacrificing any of the advantages thereof.

Having thus described the invention what is claimed is:—

1. The combination with a frame having a vertical guide-way, of a reciprocating piston and operating means therefor mounted in the frame, block sections arranged upon

each other and movable in said guide-way, said pitman being pivotally connected at one end to said block sections, retaining bars secured upon the frame and extending over the guide-way at opposite sides thereof and engaging upon the opposite longitudinal edges of one of the block sections, said bars each including a stationary section and a movable section hinged to the stationary section, and screws carried by said movable retaining bar sections whereby the same may be rigidly secured to the frame.

2. The combination with a frame, of a reciprocating pitman and operating means therefor, said frame having a guide-way, block sections slideable in said guide-way and pivotally connected to said pitman, one of said block sections having its opposite longitudinal edges rabbeted, said sections being arranged upon each other and provided in their opposed faces with recesses to receive the end of a dasher shank, retaining bars secured upon the frame and extending upon the rabbeted edges of said block sections, said bars each including a stationary section and a movable section hinged to the stationary section, and means for rigidly securing the movable retaining bar sections to the frame.

In testimony whereof I hereunto affix my signature in the presence of two witnesses.

THOMAS P. CALLICOTT.
